UNITED STATES PATENT OFFICE.

CHARLES J. PILLING, OF LANSDOWNE, AND HARVEY R. PIERCE, OF PHILADELPHIA, PENNSYLVANIA.

SURGICAL APPLIANCE.

1,279,154.

Specification of Letters Patent. Patented Sept. 17, 1918.

Application filed May 26, 1917. Serial No. 171,077.

To all whom it may concern:

Be it known that we, CHARLES J. PILLING, a citizen of the United States, residing at and whose post-office address is Lansdowne, 5 county of Delaware, and State of Pennsylvania, and HARVEY R. PIERCE, a citizen of the United States, residing at and whose post-office address is 1801 Chestnut street, city and county of Philadelphia, and State 10 of Pennsylvania, have invented certain new and useful Improvements in Surgical Appliances, of which the following is a specification.

Our invention relates to improvements in 15 surgical appliances; and the object of our invention is to provide a novel, simple and efficient appliance for use in connection with the treatment of cavities for various purposes such as the sterilization thereof by 20 the introduction of the well known Dakin's solution.

Our invented appliance includes a syringe member for closing the entrance to the cavity to be treated, and a tube extending 25 through the member, and adjustable therein, for the introduction of the Dakin's solution or other liquid, and means operative to adjust the tube within the cavity and relatively to the member. Our appliance also 30 includes an introducing or inserting member, by the aid of which the member may be inserted into the entrance to the cavity to be treated.

The appliance is particularly, though not 35 exclusively, adapted for use in the treatment of the uterus, and the member, introducer and tube adjuster, shown in the drawings hereinafter referred to are designed and adapted for this particular use.

With the above named object in view, our 40 invention consists in the novel construction and combinations of parts hereinafter described and claimed.

In the accompanying drawings, illustrating 45 our invention,

Figure 1 is a side view of our improved surgical appliance, showing the position of the parts prior to the insertion of the syringe member.

Fig. 2 is a view, similar to Fig. 1, showing 50 the position of the parts after the inser-

tion of the syringe member and the adjustment of the tubes relatively thereto.

Fig. 3 is a longitudinal section through the appliance, showing the position of the 55 parts after the release of the tubes following the adjustment thereof.

Fig. 4 is a top view of the syringe member and the tubes, as shown in Fig. 1.

Fig. 5 is a section through the syringe 60 member and tubes, on line 5-5 of Fig. 1.

Fig. 6 is a side view of the syringe member.

Fig. 7 is a longitudinal section through the syringe member on line 7-7 of Fig. 6. 65

Referring to the drawings, 2 designates a syringe member which, as herein illustrated, is substantially cylindrical in form and is adapted to be inserted into and to close the entrance to the cavity to be treated. The 70 end 3 of the member is adapted to be first inserted into the entrance to the cavity during the insertion of the member. This end 3 is herein termed the inner end of the member, and the opposite end thereof is 75 herein termed the outer end of the member.

The member 2 is provided with four passages or openings 4 and 6 which extend longitudinally therethrough and which are spaced around the axis of the member, as 80 clearly shown in Fig. 5. The openings 4 and 6 are adapted to receive two flexible tubes 8 and 9, respectively, which extend therethrough and which are longitudinally adjustable therein. The portions of the 85 tubes 8 and 9 which extend beyond the inner end of the member 2 are formed into loops 10 and 11 which cross each other, as clearly shown in the drawings. The loop portions 10 and 11 are adapted to enter the cavity to be treated, and they are provided with spaced perforations 12 to permit liquid to flow from the tubes and into the cavity. The end portions of the tubes 8 and 9, extending beyond the outer end of the member 90 2, are adapted to be connected to any suitable source of supply of Dakin's solution or other liquid, located to permit the liquid to flow by gravity through the tubes 8 and 9 and into the cavity; or instead of permitting 100 the liquid to flow into the cavity by gravity, any suitable means may be employed to

force the liquid through the tubes and into the cavity.

The design of the syringe member herein illustrated is particularly adapted for use in treating the uterus. The outer end of the member 2 is provided with an outwardly-projecting, annular flange 13 adapted to engage the external os, of the uterus to limit the inward movement of the member; and 10 the inner end of the member is provided with an outwardly-projecting, annular flange 14 of less diameter than the flange 13 and is adapted to be passed through the cervical canal and to engage the internal os 15 of the uterus and prevent accidental outward displacement of the member when in use.

The member 2 has a central passage or opening 15 extending longitudinally there- 20 through, through which gauze may be introduced to the uterus for packing the same.

The outer face of the member 2 is provided with spaced, circumferential grooves 16 which are interrupted by longitudinal 25 grooves 17. The lower or outer ends of the grooves 17 terminate in openings or passages 18 which converge from the grooves 17 to the outer end face of the member 2. The circumferential grooves 16 are connected to 30 the tube openings 4 and 6 by radial passages 19; and the circumferential grooves 16 are connected by angularly disposed grooves 20 which radiate from the outer end of the pas- sages 19.

35 The purpose of the passages 19 is to permit liquid from the tubes 8 and 9 to flow to the grooves 16, 17 and 20; the purpose of the passage 18 is to permit liquid to pass out from the grooves 17 when the member is in 40 use; and the purpose of the grooves 16, 17 and 20 is to permit liquid to reach all parts of the cervical wall.

As a convenient means to insert the member 2 into the cervix, we provide an intro- 45 ducing or inserting member 21 comprising a hollow handle 22 and a tubular arm 23 extending therefrom and suitably curved to conform to the vagina. The member 2 is adapted to be detachably mounted on the 50 free end of the arm 23 by inserting said free end into the outer end of the central opening 15 in the member; and the downward movement of the member 2 upon the arm 23 is limited by an outwardly-projecting, annu- 55 lar flange 24 on the arm 23; whereby, when the arm 23 carrying the member 2, as shown in Fig. 1, is introduced into the vagina, the arm 23 will carry the member therewith and the member may be subsequently inserted 60 into the os of the uterus by the aid of the inserting member 21. After the member 2 has been thus inserted, the arm 23 is withdrawn from the member 2 and the vagina, leaving the member in place in the os of the uterus.

65 To adjust the tubes 8 and 9 relatively to

the member 2, and to project the loop portions 10 and 11 of the tubes into the uterus, after the insertion of the member 2, as just described, we provide the following device:

Slidable within the hollow handle 22 and 70 the tubular extension 33 thereof is a rod or arm 25 having a thin upper portion which is adapted to conform to the curved portion of the tubular arm 23. Arranged adjacent to the upper end of the arm 25 is a spring 75 arm 27, the lower end of which is secured to the arm 25. The upper or free end of the spring arm 27 terminates opposite to the adjacent free end of the arm 25; and the adjacent free ends of the arms 25 and 27 are nor- 80 mally separated, as shown in Fig. 3; and the free end of the arm 27 is adapted to be sprung toward the free end of the arm 25 from the position shown in Fig. 3 to the po- 85 sition shown in Fig. 2. These adjacent free ends of the arms 25 and 27 are provided with opposing jaws 28 and 29, respectively, which are adapted to receive the tubes 8 and 9 and hold or clamp them therein when the arm 27 is sprung to move the jaw 28 toward the 90 jaw 29, as shown in Figs. 1, 2 and 4.

The arm 27 is adapted to be sprung to- 95 ward the arm 25 to close the jaws 28 and 29 by a ring 30 which surrounds the arms 25 and 27 and which is carried by the adjacent 100 end of a long, thin arm or part 31 which ex- tends through the inserting member 21, ad- jacent to the arm 25. The arm 31 is pro- vided with a guide sleeve 32 on its lower 105 end which surrounds the arm 25 and a guide sleeve 33 intermediate of its ends which sur- rounds the arm 25. The guide sleeve 32 is provided with a thumb piece 34, by means of which the arm 31 may be moved longitu- 110 dinally, guided by the arm 25, by the thumb 110 of the hand of a physician or surgeon grasps the lower end of the arm 25. When the arm 31 is thus moved upwardly to the position shown in Fig. 2, the ring 30 oper- ates to move the arm 27 toward the arm 25 115 and close the jaws 28 and 29; and, when the arm 31 is moved downwardly, or in the re- 120 verse direction, the ring 30 operates to per- mit the arm 27 to spring back to its normal 125 position, shown in Fig. 3, to open the jaws 115 28 and 29.

The arms 25 and 31 are bodily movable within the inserting member 21 and the syringe member 2 thereon, to adjust the tubes 8 and 9 relatively to the member 2 130 when the tubes are clamped within the jaws 28 and 29; and, to limit the bodily upward movement of the arms 25 and 31, when the tubes 8 and 9 are clamped within the jaws 28 and 29, a stop sleeve 35 is placed upon 135 the arm or rod 25 and provided with a set screw 36 to clamp the sleeve 35 in different positions of adjustment on the arm 25. This stop sleeve 35 is adapted to engage the bot- 140 tom of the handle 22 of the members 21 and 130

limit the upward movement of the arm 25, and thus limit the movement of the jaws 28 and 29 away from the inner end of the member 2. The rod 25 is provided with suitable 5 graduation markings with which the stop sleeve 35 is adapted to register to enable the sleeve 35 to be quickly set at any predetermined distance from the handle 22, in accordance with the extent of the desired 10 adjustment of the tubes 8 and 9 relatively to the member 2.

The upper end of the arm 31, as well as the arm 25, is made sufficiently flexible to conform to the curved portion of the tubular 15 arm 23 of the inserting members 21; and the arms 25 and 31 are adapted to be bodily withdrawn from within the inserting member 21 for any desired purpose.

The operation of the appliance is as follows:

The syringe member 2 is placed upon the end of the arm 23 of the inserting member 21, the tubes 8 and 9 are passed through the openings 4 and 6 in the member 2 and the 25 loop portions 10 and 11 of the tubes 4 and 6 are clamped within the jaws 28 and 29 and the parts occupy the position shown in Figs. 1 and 4. Measurement of the uterus to be treated is taken with the aid of a suitable 30 uterine sounding instrument, and, after the distance between the internal os and the fundus or anterior wall is determined, the stop sleeve 35 is placed upon the arm 25 a corresponding distance or a slightly less 35 distance from the handle 22.

Now, the physician or surgeon grasps the handle 22, and by the aid of the inserting member 21, passes the member 2 in through the vagina and inserts it into the cervix of 40 the uterus until the outer flange 13 of the pessary comes into engagement with the external os. During the insertion of the member 2 the cervix is expanded slightly thereby and after the inner flange 14 passes the 45 internal os, the cervix contracts around the body of the member 2 and the inner flange 14 prevents the accidental withdrawal of the member 2 from the cervix.

The arms 25 and 31 are now moved bodily 50 inward until the stop sleeve 35 engages the handle 22 thereby drawing the loop portions 10 and 11 of the tubes 8 and 9 into the uterus and into the position shown in Fig. 2, the engagement of the sleeve 35 with the handle 22 preventing the projection of the jaws 28 and 29 and the tubes 8 and 9 far enough to puncture or injure the fundus or the wall of the uterus.

This being done, the physician grasps the 60 outer end of the rod or arm 25 and places his thumb upon the part 34 and operates the sleeve 32 to move the arm 31 outwardly, thereby moving the ring 30 outwardly and permitting the jaws 28 and 29 to separate 65 and release the tube loops 10 and 11; and

following this the inserting member 21 and the tube adjusting arms 25 and 31 are bodily withdrawn from the member 2 and from the vagina, leaving the member 2 in place in the cervical canal and the outer end portions of 70 the tubes extending from the vagina.

The uterus is now packed with gauze which is inserted through the central opening 15 of the member 2 with the aid of a suitable uterine packing instrument. The 75 gauze thus inserted serves the double purpose of retaining and distributing liquid within the uterus and spreading the loop portions 10 and 11 of the tubes and holding them in position. The central opening 15 of 80 the member 2 is also packed with gauze to close the same.

The outwardly extending end portions of the tubes 8 and 9 are now connected to a suitable source of supply of the Dakin's solution or other liquid to be introduced to the uterus, and the liquid is permitted to flow through the tubes 8 and 9 and out through the perforations 12 therein by gravity, or the liquid is forced through the 90 tubes and out through the perforations therein.

The liquid passes from the perforations 12 into the passages 4 and 6 of the member 2 and into the gauze within the uterus and 95 the gauze becomes saturated with the liquid and carries it to all parts of the walls of the uterus. The liquid passes from the openings 4 and 6 through the openings 19 and fills the grooves 16, 17 and 20 and from them finds 100 its way to all parts of the cervical canal; and, further, the liquid enters the grooves 17 from the gauze within the uterus and drains through the passages 15 and 18 to a strip of gauze which is inserted to extend 105 from within the opening 15 out through the vagina.

Thus the entire area of the uterus and its cervical canal is subjected to the action of the liquid. The uterus is usually repacked 110 with fresh gauze and the liquid is introduced to the fresh gauze, at certain intervals during the process of the treatment.

At the completion of the process of the treatment, the member 2 is withdrawn from 115 the cervix and the vagina by a suitable forceps or other means or by grasping the outwardly projecting ends of the tubes 8 and 9 by hand and pulling the member and tubes from their inserted position.

We claim:

1. A syringe member having a tube extending through and beyond the ends thereof, the member being adapted to be placed in the entrance to a cavity to be treated, and the tube being adapted to permit the passage of liquid into said cavity for the treatment thereof, and an inserting member removably engaged with the syringe member, said inserting member being provided with 125

- means causing the syringe member to move with the inserting member when it is moved in one direction and to permit the withdrawal of the inserting member from the 5 syringe member when the inserting member is moved in the reverse direction.
2. A syringe member having a tube extending through and beyond the ends thereof, and having an opening therein for the reception of an inserting member, the syringe member being adapted to be placed in the entrance to a cavity to be treated, and the tube being adapted to permit the passage of liquid into said cavity for the treatment thereof, an inserting member having an end portion adapted to be placed in the opening in the syringe member and to be withdrawn therefrom after the insertion of the syringe member in the entrance of an infected cavity, 15 said inserting member being provided with means causing the syringe member to move with the inserting member when it is moved in one direction and to permit the withdrawal of the inserting member from the 20 syringe member when the inserting member is moved in the reverse direction.
3. A syringe member having a flexible tube extending therethrough and adjustable therein, the syringe member being adapted 25 to be placed in the entrance to a cavity to be treated, and the tube being adapted to permit the passage of liquid into said cavity for the treatment thereof, and means adjustable entirely through and beyond the syringe 30 member operative to adjust the tube relatively to the same.
4. A syringe member having a tube extending therethrough and adjustable therein, the syringe member being adapted to be 35 placed in the entrance to a cavity to be treated, and the tube being adapted to permit the passage of liquid into said cavity for the treatment thereof, a hollow inserting member removably engaged with the syringe 40 member, and means extending through said inserting member and operative to adjust the tube relatively to the syringe member.
5. A syringe member having a tube extending therethrough and adjustable therein, 45 in the syringe member being adapted to be placed in the entrance to a cavity to be treated, and the tube being adapted to permit the passage of liquid into said cavity for the treatment thereof, and means operative to 50 adjust the tube relatively to the syringe member, said means being movable relatively to the syringe member and including gripping jaws for the tube and means operative to open and close the jaws.
6. A syringe member having a tube extending therethrough and adjustable therein, the syringe member being adapted to be 55 placed in the entrance to a cavity to be treated, and the tube being adapted to permit the 60 passage of liquid into said cavity for the treatment thereof, and means operative to adjust the tube relatively to the syringe member, said means comprising an arm provided with jaws adapted to grip and release said tube, and a part slideable on said arm and 65 adapted to operate said jaws.
7. A syringe member having a tube extending therethrough and adjustable therein, the syringe member being adapted to be placed in the entrance to a cavity to be treated, and the tube being adapted to permit the passage of liquid into said cavity for the treatment thereof, and means operative to adjust the tube relative to the syringe member, said means comprising an arm having a bifurcated end provided with normally spaced jaws adapted to be sprung toward each other to clamp said tube and to spring apart to release said tube, and a part slideable on said arm and having a ring encircling the same adapted to close and to permit said jaws to open when said part is moved longitudinally on said arm.
8. A syringe member having a tube extending therethrough and adjustable therein, the syringe member being adapted to be placed in the entrance to a cavity to be treated, and the tube being adapted to permit the passage of liquid into said cavity for the treatment thereof, a hollow inserting member removably engaged with the syringe member, a movable arm provided with means to engage and adjust said tube when said arm is moved relatively to said inserting member, and an adjustable stop carried by said arm and adapted to engage said inserting member to limit the movement of the arm relatively to the inserting member.
9. A syringe member having two openings extending longitudinally therethrough, and a flexible tube having a loop formed therein beyond one end of said member and extending from said loop through said openings, the loop portion of said tube having spaced perforations therein, said tube being adjustable within said openings, and means operative to adjust the tube relatively to the said member.
10. A syringe member having four openings extending longitudinally therethrough, a flexible tube having a loop formed therein beyond one end of said member and extending from said loop through two of said openings, and a second flexible tube having a loop formed therein beyond the same end of said member and crossing the first named loop and extending from its loop through two of said openings, the loop portion of said tubes having spaced perforations therein, said tubes being adjustable within said openings, and means operative to adjust the tubes relatively to said member.
11. A syringe member comprising a cylindrical body having an internal opening extending therethrough, and external grooves

communicating with said opening, and a tube extending through said opening and beyond said member and having discharge perforations therein within and beyond said opening.

12. A syringe member comprising a cylindrical body having internal openings extending therethrough, and external, annular grooves communicating with said openings.

10 13. A syringe member comprising a cylindrical body having internal openings extending therethrough, and external, longitudinal and circumferential grooves communicating with each other and with said openings.

15 14. A syringe member comprising a cylind-

rical body having an outwardly extending flange on each end thereof, and grooves in the surface thereof extending through and beyond one of said flanges.

15. A syringe member comprising a cylindrical body having an outwardly extending flange on each end thereof, and internal openings extending therethrough, and grooves in the external surface thereof between said flanges and communicating with 25 said openings.

In testimony whereof we affix our signatures hereto.

CHARLES J. PILLING.
